US00D851868S

(12) **United States Design Patent** (10) **Patent No.:** **US D851,868 S**
(45) **Date of Patent:** **** Jun. 25, 2019**

(54) **BOOT COVER**

(71) Applicant: **Matthew Isaack**, Monument, CO (US)

(72) Inventor: **Matthew Isaack**, Monument, CO (US)

(73) Assignee: **Boot Quarters, LLC**, Mooresville, NC (US)

(**) Term: **15 Years**

(21) Appl. No.: **29/616,009**

(22) Filed: **Sep. 1, 2017**

(51) LOC (11) Cl. **02-04**

(52) U.S. Cl.

USPC **D2/901; D2/946**

(58) **Field of Classification Search**

USPC D2/901, 902, 907, 908, 912, 943–946,

D2/962, 969, 972–974, 976, 978

CPC A41D 17/00

See application file for complete search history.

(57) **CLAIM**

The ornamental design for a boot cover, as shown and described.

DESCRIPTION

FIG. 1 is a front right perspective view of the first embodiment of a boot cover, showing my new design.

FIG. 2 is a front elevational view thereof.

FIG. 3 is a rear elevational view thereof.

FIG. 4 is a right elevational view thereof.

FIG. 5 is a left elevational view thereof.

FIG. 6 is a top plan view thereof.

FIG. 7 is a bottom plan view thereof.

FIG. 8 is a front right perspective view of a second embodiment of a boot cover.

FIG. 9 is a rear left perspective thereof.

FIG. 10 is an enlarged detail view thereof taken from the area 10 in FIG. 9.

FIG. 11 is a front view thereof.

FIG. 12 is a rear view thereof.

FIG. 13 is a right elevational view thereof.

FIG. 14 is a left elevational view thereof.

FIG. 15 is a top plan view thereof.

FIG. 16 is a bottom plan view thereof.

FIG. 17 is a front right perspective view of a third embodiment of a boot cover.

FIG. 18 is a rear left perspective view thereof.

FIG. 19 is an enlarged detail view thereof.

FIG. 20 is a front elevational view thereof.

FIG. 21 is a rear elevational view thereof.

FIG. 22 is a right elevational view thereof.

FIG. 23 is a left elevational view thereof.

FIG. 24 is a top plan view thereof; and,

FIG. 25 is a bottom plan view thereof.

The broken lines depicting a boot represent environment that forms no part of the claimed design.
